UNITED STATES PATENT OFFICE.

CLARENCE SIKORSKI, OF DAYTON, OHIO.

ESCUtCHEON-PLATE.

1,124,819.

Specification of Letters Patent. Patented Jan. 12, 1915.

Application filed July 9, 1914. Serial No. 343,940.

To all whom it may concern:

Be it known that I, CLARENCE SIKORSKI, a citizen of the United States, residing at Dayton, in the county of Montgomery and State of Ohio, have invented new and useful Improvements in Escutcheon-Plates, of which the following is a specification.

This invention relates to certain novel and useful improvements in escutcheon plates.

In carrying out the present invention, it is my purpose to provide an escutcheon plate which will carry a lamp so located relatively to the keyhole of the guide lock that such keyhole may be illuminated to facilitate the insertion of the key in the lock.

It is also my purpose to provide an escutcheon plate which will carry an electric incandescent lamp and a switch controlling the lamp and located upon the plate within convenient reach so that the circuit of the lamp may be closed and the latter illuminated, the lamp being so positioned upon the plate that the rays of light therefrom will be projected across an opening in the plate for the night lock whereby the keyhole of the latter will be illuminated.

Furthermore, I aim to provide an escutcheon plate which may be illuminated at any time desired and whereby the lamp and switch controlling the same may be readily and quickly removed and applied to the plate.

With the above and other objects in view, the invention consists in the construction, combination and arrangement of parts hereinafter set forth in and falling within the scope of the claim.

In the accompanying drawing; Figure 1 is a view in front elevation of an escutcheon plate constructed in accordance with the present invention. Fig. 2 is a vertical central sectional view through the plate. Fig. 3 is a transverse section view therethrough.

Referring now to the drawing in detail, 1 designates a vertical escutcheon plate having the front face thereof formed to provide a sunken panel 2 ornamented in some suitable manner. Formed in the plate 1 adjacent to the upper end thereof is an opening 3 designed to receive the forward end of the night lock.

The escutcheon plate 1, approximately centrally thereof and at a point below the opening 3 is formed with an aperture, while fixed to the back face of the escutcheon

plate immediately below the aperture there-in is a switch casing 5 containing an electric circuit controlling switch embodying push buttons 6, 7 working within apertures 66 formed in the escutcheon plate and by means of which the switch may be opened and closed respectively. Leading from the upper end of the casing 5 is a conduit 8 terminating in the aperture in the escutcheon plate.

Suitably fixed to the front face of the escutcheon plate and surrounding the forward end of the conduit 8 is a semi-bowl shaped receptacle 9 opening toward the upper end 70 of the plate and seated within the receptacle 9 upon the bottom wall thereof is a receptacle 10 carrying an incandescent lamp 11, the lamp receptacle being connected in circuit with the switch 5 and with a suitable 75 source of electrical energy, the wires leading from the switch casing through the conduit 8. The inner wall of the semi-bowl shaped receptacle 9 is preferably cut out to form a reflector and, when the lamp is 80 illuminated, projects the rays of light upwardly along the outer face of the escutcheon plate and across the opening 3 thereof thereby illuminating the keyhole of the night lock so that such keyhole may be 85 readily and quickly located.

At a point below the semi-bowl shaped receptacle 9 and approximately centrally of its width the escutcheon plate is formed with an opening 12 through which passes 90 the knob spindle 13 of the door latch, a sleeve 14 surrounding the spindle and having one end rotating within the opening 12 in the escutcheon plate and the opposite end equipped with a knob 15, the sleeve 14 being fixed to the spindle 13 so that in the rotation of the knob the spindle will be revolved.

The outer face of the escutcheon plate at the marginal edges of the sunken panel 2 is 100 suitably ornamented, while the outer wall of the bowl, the outer face of the knob and that portion of the panel 2 surrounding the opening 3 are formed to produce an ornamental effect.

From the foregoing description taken in connection with the accompanying drawing, the construction and mode of operation of my invention will be readily apparent.

It will be seen that when the button 6 is 110 pushed the switch 5 will be closed and the lamp 11 illuminated whereby the reflecting

surface of the semi-bowl shaped receptacle 9 will project the light rays from the lamp 11 upwardly along the outer face of the panel and across the opening 3 therein so 5 that the keyhole of the night lock within such opening will be illuminated. When it is desired to extinguish the light the other button is pushed and the switch opened, thereby breaking the circuit and extinguishing 10 the lamp.

While I have herein shown and described one preferred form of my invention by way of illustration, I wish it to be understood that I do not limit or confine myself to the 15 precise details of construction herein described and delineated, as modification and variation may be made within the scope of the claim without departing from the spirit of the invention.

20 I claim:

An escutcheon plate having an opening formed therein adjacent to the upper end

thereof to receive the night lock, a semi-bowl shaped receptacle secured to the front face of said plate below the opening therein, 25 an electric lamp within said receptacle, the inner face of said receptacle acting as a reflector to throw the rays of light across the opening, said plate being formed with openings below said receptacle spaced apart vertically, and an electric circuit controlling 30 push button switch secured to the rear face of said plate and having the buttons thereof projecting through the last-mentioned openings and connected in circuit with said lamp 35 whereby the latter may be illuminated and extinguished.

In testimony whereof I affix my signature in presence of two witnesses.

CLARENCE SIKORSKI.
